(57) **CLAIM**

The ornamental design for a table, as shown and described.

DESCRIPTION

FIG. 1 is a top, front perspective view of a table showing a first embodiment of our new design;

FIG. 2 is a front elevational view thereof;

FIG. 3 is a rear elevational view thereof;

FIG. 4 is a left side elevational view thereof;

FIG. 5 is a right side devotional view thereof;

FIG. 6 is a top plan view thereof;

FIG. 7 is a bottom plan view thereof;

FIG. 8 is a top, front, left perspective view showing a second embodiment thereof;

FIG. 9 is a front elevational view thereof;

FIG. 10 is a rear elevational view thereof;

FIG. 11 is a left side elevational view thereof;

FIG. 12 is a right side devotional view thereof;

FIG. 13 is a top plan view of thereof; and,

FIG. 14 is a bottom plan view of thereof.

The broken lines show portions of the table that form no part of the claimed design.

1 Claim, 12 Drawing Sheets
